(57) **CLAIM**

The ornamental design for a transporter for a tissue transport system, as shown and described.

DESCRIPTION

FIG. 1 illustrates a top front perspective view of a transporter for a tissue transport system;

FIG. 2 illustrates a top rear perspective view of the transporter of FIG. 1;

FIG. 3 illustrates a front view of the transporter of FIG. 1;
FIG. 4 illustrates a rear view of the transporter of FIG. 1;
FIG. 5 illustrates a right side view of the transporter of FIG. 1;

FIG. 6 illustrates a left side view of the transporter of FIG. 1;

FIG. 7 illustrates a top view of the transporter of FIG. 1;
FIG. 8 illustrates a bottom view of the transporter of FIG. 1; and,

FIG. 9 illustrates a rear view of the transporter of FIG. 1, wherein the handle of the transporter is partially extended. The broken lines are included for the purpose of illustrating unclaimed portions of the transporter and form no part of the claimed design.
